UNITED STATES PATENT OFFICE.

ALBERT H. NELLER, OF FAIRFIELD, IOWA, ASSIGNOR TO THE LOUDEN MACHINERY COMPANY, OF FAIRFIELD, IOWA, A CORPORATION OF IOWA.

HOIST.

Application filed May 31, 1921. Serial No. 473,697.

To all whom it may concern:

Be it known that I, ALBERT H. NELLER, a citizen of the United States, residing at Fairfield, in the county of Jefferson, State 5 of Iowa, have invented a new and useful Improvement in Hoists, of which the following is a specification.

My invention relates to hoists having gearing to increase the lifting power of the 10 hoist, and it consists of an arrangement of the parts whereby a hoisting wheel is mounted at one end of the gearing and an extension or extensions are secured to the opposite end of the gearing whereby an additional 15 wheel or wheels may be mounted on said extension or extensions at some distance from the gearing and said hoisting wheel or wheels will operate in unison with the first mentioned hoisting wheel. Also, it consists 20 of braces secured to a casing which usually encloses the gearing to support the extension or extensions, and of other improved features set forth in the specification and defined in the claims.

25 In the accompanying drawings which form a part of this specification, Fig. 1 is a side perspective of a hoist mounted on an overhead track-way and embodying my invention. Fig. 2 is an enlarged perspective 30 of the part of the hoist containing the gearing and the first hoisting wheel mounted therein. Fig. 3 is a similar view of the part containing the second hoisting wheel which is mounted on the extension. Fig. 4 is an, 35 enlarged perspective of the part containing the gearing with the casing removed and certain portions partly broken away to obtain a better view of some of the interior mechanism. Fig. 5 is a vertically disposed 40 longitudinal section on line 5—5 of Fig. 4. Fig. 6 is a vertical transverse section on line 6—6 of Fig. 4, looking in the direction of the arrow. Figs. 7 and 8 are detail views which will be later explained. Fig. 9 is a 45 transverse section on line 9—9 of Fig. 8. Figs. 10 and 11 are additional detail views. Fig. 12 is a slightly enlarged transverse section on line 12—12 of Fig. 5, the cut away portion of Fig. 5 being replaced to make 50 the structure complete.

Referring to the drawings, A represents

an elevated track-way on which trolleys B are mounted. The trolleys are preferably arranged in pairs joined together by connecting devices C. D represents the main 55 frame containing the gearing and D' a supplemental frame between which and the main frame a hoisting wheel E is mounted and shown in Fig. 5. The wheel is preferably provided with sprockets e, (see Figs. 5 and 60 6) to engage the links of the hoisting chain F.

G represents an extension frame in which the second hoisting wheel is mounted. The main frame D and the extension frame G 65 are attached to the connecting devices C of the adjacent trolleys by means of a swivel containing a transverse pivot I, the object of which pivot is to prevent the bending or breaking of the swivel head should either of 70 the trolleys run off the track-way, or become so disconnected from the end of the hoist to which they are attached that said end would drop down to an approximately vertical position.

75 In Figs. 1 and 2, the main frame D is shown provided with a casing J which is removed in Figs. 4 and 5 to give a view of the interior mechanism. K represents a chain wheel upon which a hand chain L 80 is mounted and by means of which the gearing of the hoist is operated. The wheel K is mounted on a shaft M which has a small gear N on its inner end, (see Figs. 4 and 5). A revolving frame O carrying two dual or 85 differential gears P and P', the larger of which gears are in mesh with the small gear N, is mounted in the main frame. On the circumference of the main frame is an internal gear Q which is in mesh with the 90 smaller of the dual or differential gears P'. The hoisting wheel E is provided with an extension R (see Fig. 5) which is rigidly fastened by a key K', as shown in Fig. 12, or otherwise rigidly secured in the revolving 95 frame O, whereby they will turn in unison. The shaft M to which the hand wheel K is affixed, is journaled in the wheel E and its extension R, and will turn freely therein, thus causing the small gear or pinion N 100 to rotate the gears P. The smaller gears P', connected to the gears P being in mesh

105

with the stationary internal gear Q, and being also rotated, will cause the revolving frame O to rotate, which frame being affixed to the hoisting wheel E will cause it to rotate, and thus either raise or lower the hoisting chain F according to the direction of the rotation. Consequently a pull on the hand chain L will operate the entire mechanism and the leverage on the hoisting chain F will be largely increased by the gearing.

To provide for the operation of the second hoisting chain H, I use a shaft S, preferably of tubular material. I affix to the revolving frame O, as shown in Figs. 4 and 5, a coupling member T has a portion T' adapted to be inserted in the adjoining end of the tubular shaft S, and to be preferably secured thereto by bolts *a*. The coupling member T is preferably connected to the revolving frame O by passing the extended ends of the axles *t*, on which the gears P and P' are mounted, through holes in the extended ends of the coupling member and securing them in this position by cotter pins, as shown in Figs. 4 and 5.

The other end of the shaft S is passed through openings in the extension frame G where it may be freely rotated by its connection with the revolvable frame O. On this end of the shaft and within the frame G is affixed a hoisting wheel to receive the hoisting chain H. This hoisting wheel (not shown in detail in the drawings) is of the same diameter as the wheel E and is preferably provided with similar sprockets to engage and operate the chain H in unison with the chain F.

To hold the extension frame G in fixed relation with the main frame D, I use braces U, preferably of tubular material and three in number. Tubular shaped sockets V are formed on the face of the casing J and also on the adjacent face of the frame G, and the ends of the braces U are inserted in said sockets and are secured therein preferably by bolts *b*. In use the casing J is securely held in place on the frame D by means of bolts *d*, (shown in Fig. 4) and therefore the frames D and G will be securely held in fixed relation by the braces U.

The upper slack ends of the hoisting chains F and H, designated by F' and H', after passing over the hoisting wheels, are preferably connected to adjacent ends of the extension shaft S, and are arranged to wind and unwind thereon as the lower ends of the chains which carry the loads are raised and lowered. To assist in winding and unwinding the chains, I use guides W to slide on the shaft S and also on one of the braces U. To prevent the sticking of these guides in sliding on the shaft S and brace U, (preferably the lower brace) I use rollers X, as most plainly shown in Fig. 10.

The rollers are located on the guides so as to run on opposite sides of the brace U and will thereby prevent it from catching or sticking thereon, as it would be liable to do without the rollers.

In using the hoist, the loads which are attached to the lower ends of the hoisting chains F and H, (loads not shown), will sometimes swing around and twist the chains so they will not run straight to the hoisting wheels but will climb on one side or the other of the sides or the sprockets *e*, and in such cases the hoisting wheels are liable to become locked, or the chains or the wheels, or both, are liable to be materially damaged. To overcome this trouble, I use chain straightening guides Y and Y', located on opposite sides and below the horizontal meridian of the hoisting wheels. The load ascending ends of the chains are passed through the former and the descending or slack ends pass down through the latter.

As shown by Figs. 8, 9 and 11, the hollow portions of these guides, through which the chains pass, are made to loosely fit the general contour of the links of the chains, and the chains will be straightened in passing through them, by the angular corners *g* coming in contact with the sides of the links should the chains become twisted. By this means the chains will be straightened and will be prevented from climbing upon the edges of the hoisting wheels. The guide Y is pivoted at its upper end between the frames D and D' on one side of the wheel E at Z, and the guide Y' is pivoted near its lower end between the frames on the other side of the wheel E at Z', as shown in Fig. 6.

It is necessary sometimes that the lower end of the guide Y should be free to swing side-wise to a certain extent to accommodate the line of draft of the chain. Therefore it is pivoted at its upper end. This is not necessary in the descending or slack ends F' and H' of the chains, and for this reason the guide Y' is pivoted near its lower end. The guide Y' is provided with an upstanding prong *h* which is adapted to project into the recess in the center of the hoisting wheel between the sides *e*, to prevent the slack chain from following around the wheel on its under side. Also, with upstanding prongs *i* to further assist in separating the slack chain from the wheels to form the loop F', and also the loop H'.

It is obvious that additional extensions may be made by placing additional trolleys on the track-way and connecting to said trolleys additional extension frames G, similar to that shown in Figs. 1 and 3. Sockets V will have to be placed on the outer face of the frame G and the additional frame or frames if used, except the last one similar to those on the inner face of the frame G, or other

means will have to be provided for the attachment thereto of additional extension braces, similar to the braces U. An additional extension shaft or shafts will also 5 have to be provided and coupling means will have to be used to connect said shaft or shafts to the preceding extension shaft.

As shown in the drawings, the hoist is adapted to lift two separate loads in unison 10 at one operation, the loads being attached to the chains F and H, but by using additional extension frames and extension shafts with wheels thereon carrying hoisting chains, as explained, it will be adapted 15 to lift additional loads. On the other hand, if only one load is to be lifted, the extension shaft S and braces U may be disconnected from the gearing and from the casing J, in which case it may be used as an 20 ordinary single hoist, thus making it adaptable to a variety of uses either single or plural as may be required. Also, the loads, whether single or plural, after being lifted may be readily carried along the elevated 25 track-way. It will be observed, as most plainly shown by Figs. 1, 3, 5 and 6, that in addition to the transverse pivot I, there is also a longitudinal pivot m in the swivel connecting together the trolleys and the 30 frames D, D' and G. This longitudinal pivot will permit the tilting of the hoist side-wise to a considerable extent, should this be required, without straining the swivel connection or disarranging the trolleys 35 on the track-way. A guard for the chain wheel K is represented by n and r is a pivoted cover for an opening in the casing J, said opening being convenient for the oiling of the gearing within the casing. 40 In Fig. 5 a common arrangement is shown at X' and adjacent thereto, whereby the chain wheel K will be automatically thrown into rigid connection with the shaft M or be released therefrom, which arrangement 45 being common in the prior art need not be explained.

The hoist is complete in its construction, being designed to meet all requirements under all conditions. I do not however, 50 limit myself to the exact construction shown in the drawings. What I claim as my invention is:

1. In a hoist having trolleys to run upon and be supported by an overhead track-way, the combination of a main frame containing gearing to increase the lifting capacity of the hoist; a hoisting wheel connected to the gearing at one end of said main frame; an extension shaft at the other 55 end of the frame; coupling means to connect the adjacent end of the extension shaft to the gearing; an extension frame having trolleys to run upon and be supported by the overhead track-way, the outer end of 60 the shaft being journaled in said extension frame, and a hoisting wheel on the outer end of the extension shaft adapted to be rotated in unison with the wheel on the other end of the extension frame.

frame, and a hoisting wheel on the outer end of the extension shaft adapted to be rotated in unison with the hoisting wheel at the other end of the main frame.

2. In a hoist having trolleys to run upon and be supported by an overhead track-way, the combination of a main frame containing gearing to increase the lifting capacity of the hoist; a revolving frame in the main frame connected to said gearing; 70 a hoisting wheel affixed to one end of the revolving frame; an extension shaft coupled to the other end of the revolving frame, an extension frame having trolleys to run upon and be supported by the overhead track-way, the outer end of the extension shaft being journaled in said extension frame, and a hoisting wheel on the outer end of the extension shaft adapted to be rotated in unison with the wheel on the other 75 end of the revolving frame.

3. In a hoist having trolleys to run upon and be supported by an overhead track-way, the combination of a main frame containing gearing to increase the lifting capacity of the hoist; a revolving frame in the main frame connected to said gearing; 90 a hoisting wheel affixed to one end of the revolving frame; an extension shaft of tubular material; a coupling casting connected to the other end of the revolving frame and having an extension inserted in the adjacent end of the tubular shaft and fastened therein; an extension frame having trolleys to run upon and be supported by 100 the overhead track-way, the outer end of the extension shaft being journaled in said extension frame, and a hoisting wheel on the outer end of the extension shaft adapted to be rotated in unison with the hoisting 105 wheel on the other end of the revolving frame.

4. In a hoist having trolleys to run upon and be supported by an overhead track-way, the combination of a main frame containing gearing to increase the lifting capacity of the hoist; a revolving frame in the main frame connected to said gearing; a hoisting wheel affixed to one end of the revolving frame; an extension shaft of tubular material; a T-shaped coupling casting having its outstanding portions connected to the other end of the revolving frame and the stem of the T inserted in the adjacent end of the tubular shaft and fastened therein; an extension frame having trolleys to run upon and be supported by the overhead track-way, the outer end of the extension shaft being journaled in said extension frame, and a hoisting wheel on 115 the outer end of the extension shaft adapted to be rotated in unison with the wheel on the other end of the revolving frame.

5. In a hoist having trolleys to run upon and be supported by an overhead track-

130

way, the combination of a main frame containing gearing to increase the lifting capacity of the hoist; a hoisting wheel connected to the gearing at one end of said main frame; an extension shaft at the other end of the frame; coupling means to connect the adjacent end of the extension shaft to the gearing; an extension frame having trolleys to run upon and be supported by the overhead track-way, the outer end of the shaft being journaled in said extension frame; a hoisting wheel on the outer end of the extension shaft adapted to be rotated in unison with the hoisting wheel at the other end of the main frame, and hoisting chains mounted upon said hoisting wheels.

6. In a hoist having trolleys to run upon and be supported by an overhead track-way, the combination of a main frame containing gearing to increase the lifting capacity of the hoist; a hoisting wheel connected to the gearing at one end of said main frame; an extension shaft at the other end of the frame; coupling means to connect the adjacent end of the extension shaft to the gearing; an extension frame having trolleys to run upon and be supported by the overhead trackway, the outer end of the shaft being journaled in said extension frame; a hoisting wheel on the outer end of the extension shaft adapted to be rotated in unison with the wheel at the other end of the main frame; and means to operate the hoisting gearing.

7. In a hoist having trolleys to run upon and be supported by an overhead track-way, the combination of a main frame containing gearing to increase the lifting capacity of the hoist; a casing attached to said frame to enclose the gearing; a hoisting wheel connected to the gearing at one end of the frame; an extension shaft at the other end of the frame; coupling means to connect the extension shaft to the gearing; an extension frame having trolleys to run upon and be supported by the overhead track-way, the outer end of the shaft being journaled in said frame; a hoisting wheel on the outer end of the extension shaft adapted to be rotated in unison with the hoisting wheel at the other end of the main frame, and a series of braces surrounding the extension shaft and affixed to the adjacent faces of the casing and the extension frame, whereby the extension frame and the casing, and the main frame attached thereto, will be securely held in fixed relation.

8. In a hoist having trolleys to run upon and be supported by an overhead track-way, the combination of a main frame containing gearing to increase the lifting capacity of the hoist; a casing attached to said frame to enclose the gearing; a hoisting wheel connected to the gearing at one end of the frame; an extension shaft at the other end of the frame; coupling means to connect the extension

shaft to the gearing; an extension frame having trolleys to run upon and be supported by the overhead track-way, the outer end of the shaft being journaled in said frame; a hoisting wheel on the outer end of the extension shaft adapted to be rotated in unison with the hoisting wheel at the other end of the main frame; a series of sockets on the adjacent faces of the casing and the extension frame surrounding the extension shaft, and a series of braces having their ends affixed in said sockets whereby the extension frame and the casing with the main frame attached will be securely held in fixed relation.

9. In a device of the character described, a plurality of trolleys adapted to run on an overhead trackway a distance apart, a separate hoisting frame connected to each separate trolley, extended means connecting the hoisting frames together and adapted to operate their mechanism in unison, and a transverse pivot in each connection between each hoisting frame and the trolley to which it is connected, whereby should either trolley be dropped to a position below another the transverse pivot in the connection between it and the hoisting frame will be free to accommodate the mechanism to the accidental position and guard against breakage or dis-arrangement.

10. In a device of the character described, a plurality of trolleys adapted to run on an overhead trackway a distance apart, a separate hoisting frame connected to each separate trolley, a swivel in each connection, extended means connecting the hoisting frames together and adapted to operate their mechanism in unison, and a transverse pivot in each swivel connection, whereby should either trolley be dropped to a position below another the transverse pivot in the connection between it and the hoisting frame will be free to accommodate the mechanism to the accidental position and swing around to guard against breakage or disarrangement.

11. In a device of the character described, a plurality of trolleys adapted to run on an overhead trackway a distance apart, a separate hoisting frame connected to each separate trolley, a swivel in each connection, extended means connecting the hoisting frames together and adapted to operate their mechanism in unison, and a double pivot, one transverse and the other longitudinal in each connection, whereby should either trolley be dropped to a position below another the pivots in the connection between it and the hoisting frame will be free to accommodate the mechanism to the accidental position and swing around to guard against breakage or disarrangement.

12. In a hoisting device having a hoisting wheel; a horizontally disposed shaft connected to said wheel and adapted to be ro-

tated in unison therewith; a hoisting chain passed to assist it in winding and unwinding passed over the hoisting wheel and its slack end arranged to wind and unwind on said horizontal shaft; a supplemental member 5 extending below and parallel with the shaft; a guide mounted on said shaft and supplemental member through which the chain is

passed to assist it in winding and unwinding on the shaft, and rollers journaled in said guide on each side of the supplemental member, whereby the guide will be prevented from sticking on the member.

Fairfield, Iowa, May 24, 1921.

ALBERT H. NELLER.
